(57) **CLAIM**

The ornamental design for a valve with tactile position indication, as shown and described.

DESCRIPTION

FIG. 1 is a top, front perspective view of a valve with tactile position indication embodying our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, rear perspective view thereof, shown with the cap removed; and,

FIG. 9 is a front view of the valve shown mounted to an ostomy pouch.

The broken lines depict portions of the valve body and, in FIG. 9, a pouch, none of which form a part of the claimed design.
